RAILWAY SLEEPING CAR

James K. Tully, Evanston, and Basil E. Jones,
Flossmoor, Ill., assignors to The Pullman Company, Chicago, Ill., a corporation of Illinois

Application March 22, 1941, Serial No. 384,681

40 Claims. (Cl. 105—315)

This invention relates to railway sleeping cars and has for its primary object the provision of a car having permanently separate and independent compartments at upper and lower levels upon the respectively opposite sides of a central longitudinal aisle with each compartment having complete toilet facilities and including beds adapted to be disposed out of the area of the normally usable space of the respective compartments with all of the beds at one level being foldable endwise into a wall and those at the other level slideable endwise into a recess to clear the respectively usable areas, whereby such compartments are convertible for either day or night use.

The invention contemplates a bed foldable endwise into a wall of a compartment, but of less length than the compartment, and having an extension articulated therewith movable from a folded position, in the closed position of the bed, to a horizontal mattress-supporting position in the open or nighttime position of the bed. A feature of the invention is the association of a seat and folding backrest with the bed, with the backrest movable to inoperative position as the bed is opened and, wherein the underneath area of the seat incorporates balancing mechanism adapted to provide for the easy operation of the folding bed as it is manipulated from one extreme position to the other.

An important object of the invention is the provision of a slideable bed movable endwise from a position of use at nighttime, wherein it overlies the seat provided for daytime occupancy, into a recess provided therefor and wherein it occupies space not otherwise usable. The bed moves in a horizontal position at all times on antifriction rollers and is provided with means for supporting a free end of the bed at the position of the entrance to the compartment.

A further and important object of the invention is the provision of upper and lower compartments at opposite sides of a central longitudinal aisle disposed wholly out of overlapping relation, but wherein a greater number of compartments may be provided than if the compartments were all disposed at the same level.

The foregoing and other objects, which will become apparent as the description proceeds, are attained by the construction and arrangement more fully hereinafter to be described and shown in the accompanying drawings, wherein

Fig. 1 is a general perspective view of a portion of a railway car having portions broken away better to reveal the compartments at upper and lower levels constructed and arranged in accordance with this invention;

Fig. 2 is a transverse sectional view taken on the line 2—2 of Fig. 1 showing the compartment at the lower level with the bed at one side slid out for occupancy and that at the other side dis-

posed in its recessed position where it is concealed, and, further, showing the folding washstand open for use;

Fig. 3 is a longitudinal sectional view taken on the line 3—3 of Fig. 2 showing compartments at an upper and a lower level, each made up for daytime occupancy;

Fig. 4 is also a longitudinal sectional view taken on the line 4—4 of Fig. 2 showing the compartments at upper and lower levels made up for nighttime occupancy with the beds each in the open position;

Fig. 5 is a longitudinal plan sectional view taken on the line 5—5 of Fig. 4 through the compartments at upper and lower levels and revealing the similarity of the plan arrangements with respect one to the other;

Fig. 6 is a longitudinal plan sectional view taken on the line 6—6 of Fig. 4 wholly beneath the level of the upper compartment and through the bed recess for the lower compartment showing the disposition of the bed in its retracted position;

Fig. 7 is a cross sectional view taken on the line 7—7 of Fig. 5, through the upper level compartment, showing the partition opposite the folding bed and seat, and having the folding washstand in open position;

Fig. 8 is a cross sectional view taken on the line 8—8 of Fig. 3, through an upper level compartment, showing the folding bed in its closed upright position with the seat in the daytime occupancy position;

Fig. 9 is an enlarged fragmentary detail view illustrating the bed and folding seat pivot arrangement for the upper level compartment and showing the bed balancing mechanism together with the bed extension for supporting the mattress;

Fig. 10 is an enlarged fragmentary plan view of the articulated bed extension for the folding bed; and

Fig. 11 is a fragmentary detail view of the antifriction roller track arrangement for the sliding bed.

In the drawings 10 represents a railway car having sidewalls 11 and 12 and longitudinal partitions 13 and 14 defining a central aisle 15. Between the partitions 13 and 14 and the respective side walls 11 and 12 are compartments 16 and 17 at upper and lower levels, respectively, and disposed at opposite sides of the central aisle. The upper and lower compartments at each side of the aisle are separated by partitions 18 and 19 at opposite ends of the various compartments and extending from the respective side walls to the respectively associated aisle partitions. The partitions 19 extend continuously from the floor 20 of the car 10 to the roof framing 21, as best shown in Figs. 3 and 4, and the partitions

18 extend from the roof framing to floor 22 of upper compartments 16. The partitions 19 are each disposed in a single plane and continuous except for opening 23 which provides access to luggage compartment 24 provided for each upper compartment and which is disposed over the ceiling 25 of lower compartment 17. Rear wall 26 defines the depth of the luggage compartment.

Partitions 18 as best shown in Figs. 3, 4 and 5 are of substantial depth for a purpose hereinafter to appear. Each of the compartments 16 is provided with a bed 27 foldable endwise into the respective partitions 18 where it is retained by spring-pressed latches 28 disposed in respectively opposite side walls 29 of bed recess 30 and which are released by mechanism 31 including pushrods operatively associated with operating handle 32 and adapted to push the latches 28 out of engagement with catches 33 on opposite sides of the bed 27 to permit withdrawal of the bed from the recess 30. The bed is hingedly mounted in the partition recess as at 34 by means of a bracket 35 secured in the recess 30, adjacent the lower end thereof, having an upwardly opening slot 36 adapted to cooperate with trunnion 37 forming part of bracket 38 secured to the bed all as best shown in Fig. 9. The horizontal depth of partition 18 is greater at 39 to provide an overhanging support 40 for seat 41 and the hinge mechanism 34 for the folding bed is disposed substantially at the position of this seat. As best shown in Fig. 4, seat 41 conceals bed-balancing mechanism including springs 42 anchored to the seat support 40 at 43 and having sprocket chains 44 secured to their respectively opposite ends and passing over sprockets 45 pivotally secured to the brackets 35 and then connected to the bed 27 at 46 and at that side of the pivot 34 opposite the free end of the bed to exert a force thereon tending to close the bed, thus facilitating the operation of the bed. Backrest 47 for the seat 41 is fixed to the bed 27 and movable therewith to an inoperative, inverted position as the bed is opened for use and to an upright position for use as the bed is closed. Upholstered fixed armrests 48 extend between and are secured to the partition 18 and the seat support 40 at opposite sides of the seat and backrest 41 and 47 respectively.

The partition 18 is offset at 49 to provide a horizontal shelf 50 having an arcuate portion 51 connecting the shelf with the vertical rear wall 52 of the bed recess and which forms the dividing wall of the lower compartment 17. It will be noted that the hingedly mounted bed 27 does not afford a full length bed but the shelf 50 provides a support for a bed extension 55, foldable into the bed recess 30 and movable automatically with the bed to an operative horizontal position of rest on the shelf 50. As best shown in Figs. 9 and 10, the extension 55 comprises a substantially flat plate having a reinforcing rod 60 extending across its edge next adjacent to the lower edge of the bed 27 and about which the extension plate 55 is wrapped, or folded, and secured. The rod 60 extends beyond the respectively opposite sides of the extension plate to engage flanged track guide members 61 and 62 mounted upon the opposite side walls of bed recess 30 in position to support that end of the extension out of engagement with the shelf 50.

The tracks 61 and 62 are of such length as to permit of the full movement of the extension into and out of the bed recess as the bed is closed or opened. The slidible extension 55 is connected to the bed 27 by means of links 64 disposed at

opposite sides of the bed and extension and which are pivotally connected to the rod 60 at the respective ends between the extension and the tracks 61 and 62 and to the bed 27 at each side, 5 as at 65. The opposite or far end of the extension 55 is slightly arcuate, as at 66, and is supported by means of antifriction rollers 67 on the arcuate portion 51 between shelf 50 and dividing wall 52. The rollers 67 are mounted upon a reinforcing rod 68 extending across the free end of the extension and about which it is folded and secured. The extension 55, as the bed 27 is moved from an open to a closed position, is adapted, 10 by means of the rollers 67, to ride up the arcuate portion 51 and the wall 52 to an inclined position in the fully closed condition of the bed, at which time the connecting links 64 allow sufficient space 15 to accommodate a folding mattress between the closed bed and upright extension, as best disclosed in Fig. 9. The bed 27 is adapted to receive a mattress 69 provided with a foldable extension portion 70 hingedly secured thereto at 71 and which, in the open position of the bed, is adapted to provide a full length horizontally flush sleeping surface and, in the closed position of the bed, to fold up automatically as the extension 55 rides up the wall 52 and be accommodated within the recess 30. Both conditions of the folding bed arrangement are illustrated in Fig. 9 from which the relative positions may readily be ascertained. 20 A light 72 in the bed recess 30 provides illumination for reading when the bed is open, and fixtures 86 on the side and aisle walls provide light for reading in the closed position of the bed.

30 The partition 18 contains a shoe locker having door 73 providing access from the compartment 16 and a door 74 affording access thereto from the aisle 15. This partition also contains a shoe locker 76 having a door 77 affording access from the compartment 17 and a door 78 providing access thereto from the aisle. A space 79 in this partition provides accommodation for a carafe 80.

40 A combination member 81 is provided in compartment 16 incorporating the toilet facilities for this room, including a covered hopper 83 and a folding washstand 84. The combination member is disposed in that corner of the room away from partition 18 and adjacent to partition 19 and aisle partition 13 and where the enclosed hopper is overlapped by the bed 27 in its open 45 position which is supported at this free end on ledge 85 on the partition 19. A mirror 87 is disposed over the folding washstand 84 having a lighting fixture 88 thereover. A window 90 is disposed in the side wall 11 of the compartment 16 at a level convenient to a person using the seat 41 and alongside of which the bed 27 is disposed when open.

50 A single step 91, having a lighting fixture 92 at the edge thereof adapted to show a light to the top and front respectively, provides access to the level 22 of the compartment 16 through doorway 93 which may be closed by sliding door 94 receivable in pocket 95 in the aisle partition 13 and having locking handles 96 disposed upon the inner and outer sides for ready manipulation of the door.

55 It is to be noted that the surface of the partition 18, out of which the bed 27 opens, slopes 60 rearwardly from the seat position towards the top, as best shown in Figs. 1, 3 and 4, whereby the seat back 47 is disposed at a more comfortable reclining angle and further provides an additional safety feature in that the bed 27, in the event 65 it is not fully closed at the time the compart-

ment is made ready for daytime occupancy, will not be caused to open suddenly by sudden starts or stops of the vehicle of which it forms a part, but will tend always to move towards fully closed, locked position. Sloping of the surface of the partition also provides greater space in bed recess 30 for the accommodation of folding mattress 70 and a pillow 97 in the closed daytime position of the bed and, due to the increased area in the upper portion of the compartment, creates an impression of greater spaciousness.

As best shown in Figs. 3 and 4, no part of the upper compartment 16 overlies the lower compartment 17, and where the upper compartment has a pivotally mounted folding bed the lower compartment is provided with a bed of fixed full length slidably mounted to move from a concealed, inoperative position to an extended position in the compartment for use. The sliding bed 100, for the lower compartment 17, is best shown in its two extreme positions of movement in Figs. 4 and 6 respectively. The bed comprises a bunk or frame 101 in the form of an open top box like receptacle adapted to receive a full length mattress 102 and having brackets 103 secured at intervals along the outer side walls thereof, having trunnions 104 affording bearings for ball bearing mounted rollers 105 which are adapted to support the bed for relative sliding movement in tracks provided therefor. A track 106 is mounted upon the side wall 11 for support of the bed on that side and extends the full length of the movement of the bed and therefore supports the bed on this side in both fully open and retracted positions. A cover rail 107 is secured to the side wall 11 in position to overlie the track 106 and the rollers 105. The bed 100 is adapted to move from a fully concealed, retracted or daytime position beneath the floor 22 of compartment 16 and partition 18 to a fully extended open or nighttime position in the compartment 17. The bed is supported at the opposite side by means of the rollers 105, engaging a track 108, secured to vertical longitudinally extending panel 109 providing a support from the car floor 20. The panel 109 is of approximately the same height from the floor as the bed 100 and extends from the partition 19 to a combination member 111 in the lower compartment, and a horizontal member 117 of this same extent closes the space between the top of panel 109 and the aisle partitions 18 and 14, as best shown in Figs. 7 and 8, to prevent anything from the bed from falling into this space. An end member 110 closes the space between the members 109 and 117 and the combination member 111. A horizontal member 118 is disposed immediately beneath the bed frame 101 between the respective panels 109 and the car side walls 11 and 12 and extending from the partition 19 to a vertical transverse wall 119, as best shown in Figs. 3 and 4, and which extends from the respective panels 109 to the side walls 11 and 12 and from the members 118 to the car floor 20. This member 118 prevents any part of the bed from falling into the space 120, which otherwise would be exposed by the withdrawal of the bed 100 from the recess 121 thus formed.

It will be noted that the bed frame, or bunk, 101 is not carried at its front corner from the panel 109 by means of one of the rollers 105, but, instead, is supported by means of a corner bracket 122 having a laterally extending part 123 adapted removably to interlock with a slotted support bracket 124 on the panel 109, thereby to retain the bed in retracted position against move-

ments of the vehicle tending to displace it. The corner bracket is adapted also to lock the bed in extended, open position as will hereinafter appear. The space 125 beneath the bed 100, in its normally closed position, as best shown in Fig. 3, may be utilized for the storage of luggage as may the space on the bed beneath the seat support 48 and shelf 50 when the bed is not in use, if desired. The bed 100, in its retracted position, is concealed by means of a curtain 126 suspended from a curtain rod 139 and extending between the side wall 11 and aisle partition 13 and from the lower portion of wall 52 over the end of the bed and which may be withdrawn when the bed is extended for use. While the curtain 126 is indicated as closing this space, any other type of closure might be utilized, such as a rollaway partition or doors or the like.

A seat 130 is provided in compartment 17 adjacent to the partition 19 and having an associated backrest 131 supported against this partition. The seat and backrest may be supported entirely from the partition 19 or from the side wall 11 and aisle wall 13 or the floor 20 or in any manner desired from any one or combination of these elements. A bracket 132 connects the seat and backrest at that side away from the side wall 11 and is provided with a vertically opening slot 133 adapted to receive the lug 123 on the bed. The bracket 132 is rigidly mounted and therefore provides a fixed support for the cooperating end of the bed 100 which, by means of the interlocking engagement between the part 123 and the slot 133, is thereby retained in fully extended position against any jarring movement tending to dislodge it with the bed 100 in overlapping relation to the seat 130. The bracket 132 might form part of an armrest for the seat 130 or be entirely dissociated from the seat so long as its supporting and locking relation, with respect to the bed, is retained. The seat and backrest 130 and 131 are disposed alongside of window 135 mounted in the side walls 11 or 12, and a sliding door 136 is disposed at the opposite side of the seat and adapted to be received in a pocket 137 provided therefor in the aisle partition 13 which permits of the opening movement of the door. Locking handles 138, on opposite sides of the door, provide for its operation from either the aisle side or from within the room. It will be noted that the floor level 75 of the aisle 15 is coincident with the floor level of the compartments 17 and only one step is necessary between the aisle floor and room 16.

The combination member 111 in compartment 17 includes folding washstand 140 and concealed chair hopper 141 and is disposed at the aisle partition between the wall 52 and entrance door 136 where it is overlapped by the bed 100 when the bed is made ready for occupancy. The combination member 81, in compartment 16, is disposed at the aisle partition in the corner of the room between partition 19 and the entrance door 94 and it will be noted in each instance that the respective beds 27 and 100 overlie the hoppers 83 and 141 when the beds are extended, wherefore, in order to use the hoppers, which are each covered by a hinged cover seat, it is necessary first to remove the bed from its overlapping relation thereto before the hinged covers can be raised to expose the hoppers. Hence, the respective beds are made easily operable by the counterbalancing mechanism 42 and the ball bearing mounting rollers 105.

A large mirror 142, having a light 143 disposed thereover, is secured upon the face of wall 52 in the compartment 17 where it is not only decorative but most readily accessible with respect to use of the folding washstand 140. A reading light 144 is provided on the side wall adjacent the seat 130 and an overhead ceiling light 145 provides general illumination for the compartment 17.

An important feature of this arrangement, as best shown in Fig. 4, is that no part of the usable area of the compartment 17 is overlapped by any usable area in the compartment 16 and while the foot area of lower bed 100 is overlapped by the head portion of upper bed 21 it will be seen that the area is effectively insulated against the transmission of any sound by the thicknesses of the upper compartment seat 41, folded backrest 47, and the mattress 69 and pillow 97. The floor 22, in upper compartment 16, overlies only the recess 121 for the bed 100 of the lower compartment 17.

It will be noted that by the use of the particular arrangement of beds, as disclosed herein, with the sliding beds all disposed at one level and the pivotal folding beds all at another level, a greater number of rooms can be gotten into a vehicle than would otherwise be possible and the transportation costs therefore correspondingly reduced. A further feature of the invention is that the rooms are defined by dissimilar partitions at opposite ends in that alternate partitions throughout the length of the vehicle, are adapted to the accommodation of folding beds for the upper rooms, and the rooms are disposed in pairs of an upper and a lower between similar partitions whereby the utmost compactness is achieved and overlapping of usable areas is avoided.

From the foregoing it will be seen that there has been provided an arrangement involving rooms of different types adapted co-operatively to be associated with each other to obtain a greater number of rooms in a vehicle of given size and wherein the rooms are disposed at opposite sides of a central longitudinal aisle at different levels and readily accessible from the aisle with the aisle level coincident with the level of certain of the rooms and involving folding beds in the rooms at one level and sliding beds in all of the rooms at the other level. It is to be noted that all of the available space throughout the entire vehicle has been utilized to the greatest advantage with the result that each room is so designed as to make use of its area in such manner that waste space and unused portions are wholly eliminated and in which every portion of the room has a function. By the efficiency of the arrangement the greatest number of passenger accommodations may be incorporated in a vehicle without sacrificing the comfort of the occupants and without detracting from the standard of railway sleeping accommodations heretofore maintained. An important advance of the present construction over prior arrangements having rooms at two levels lies in the fact that the space over the seat in every room extends to the ceiling of the respective rooms, whereby the confined areas over the seats of earlier designs caused by overhanging shelves or bunks, or even floor areas, as a result of the overlapping of usable areas, is completely eliminated and the occupant afforded the luxury and unrestricted spaciousness of a high ceiling with attendant safety flowing from the elimination of the hazard always present with a structure immediately overhanging the head of a seated occupant. The fact that all of the seats

in the present arrangement face in the same direction avoids the necessity for any occupant to ride with his back in the direction of movement of the vehicle, which is an advantage in the elimination of complaints from the traveling public, some members of which object to such manner of riding over extended distances. In this design the only overlapping areas between upper and lower accommodations is utilized for the accommodation of the respective beds for the individual rooms, in that one is disposed above the offset in the intermediate partition and the other is disposed beneath this offset portion, whereby this otherwise unusable space is utilized for the accommodation of the facilities not ordinarily used in daytime.

What is claimed is:

1. In a vehicle, a lower room and an upper room having its floor at a level higher than the floor of the lower room and wholly displaced longitudinally of the vehicle from the normally usable space of the lower room, a bed in the upper room retractable for daytime use of the room and wholly displaced longitudinally of the vehicle from the standing and seating area of the lower room, a bed in the lower room under the bed of the upper room retractable for daytime use of the room and disposed adjacent to the floor of the upper room in retracted position, each of said beds when disposed in operative position having its longitudinal axis disposed longitudinally of the vehicle and extending substantially full length of the respective rooms, a separate storage space beneath the upper room accessible to the lower room, and a separate storage space above the level of the lower room accessible to the upper room.

2. In a vehicle, a lower room and an upper room having its floor at a level higher than the floor of the lower room and wholly displaced longitudinally of the vehicle from the normally usable space of the lower room, a dividing partition between the rooms having a horizontal offset, a bed in the upper room retractable for daytime use of the room and wholly displaced longitudinally of the vehicle from the standing and seating area of the lower room, a relatively fixed seat adjacent said dividing partition at said offset, a relatively fixed seat in the lower room opposite said dividing partition facing in the same direction as said seat at the offset, and a bed in the lower room under the bed of the upper room retractable for daytime use of the room and disposed adjacent to the floor of the upper room, each of said beds when disposed in operative position having its longitudinal axis disposed longitudinally of the vehicle and extending substantially full length of the respective rooms.

3. In a vehicle, a lower room and an upper room having its floor at a level higher than the floor of the lower room and wholly displaced longitudinally of the vehicle from the normally usable space of the lower room, a relatively fixed seat in the upper room, a bed in the upper room retractable for daytime use of the room and wholly displaced longitudinally of the vehicle from the standing and seating area of the lower room, a relatively fixed seat in the lower room facing in the same direction as said seat in the upper room, and a bed in the lower room under the bed of the upper room retractable for daytime use of the room and disposed adjacent to the floor of the upper room, each of said beds when disposed in operative position having its longitudinal axis disposed longitudinally of the vehicle and

extending substantially full length of the respective rooms.

4. In a railway car, two side walls and two end walls defining a passenger compartment, one of said end walls being provided with a recess and the opposite end wall dividing the compartment from an immediately adjoining compartment and separating a portion of the standing room space of the first compartment from a portion of the standing room space of the second compartment, a bed foldable lengthwise into said recess and extensible into substantial engagement with said opposite end wall, said bed when disposed in operative position having its longitudinal axis extending longitudinally of the car, and a combination toilet member in the corner formed by said opposite end wall and one of the side walls and comprising a hopper and a superposed washstand, said hopper being overlapped by the bed when the bed is extended, and said washstand being foldable against one of the walls forming said corner to permit the bed to be moved between folded and extended positions.

5. In a railway car, a series of passenger compartments disposed in adjoining relation along the length of the car, transverse partitions separating adjacent compartments, each alternate partition being relatively thick and including a recess, and each intervening partition separating a portion of the standing room space of the two compartments which it separates, a toilet member including a washstand in the corner of certain of said compartments formed by the separating partition and a lengthwise wall, a bed foldable lengthwise in the recess in each of said last named compartments and being long enough to extend substantially from the recessed partition to the separating partition when extended, and means mounting the bed for extension to a position adjacent the toilet member, said bed when disposed in operative position having its longitudinal axis disposed longitudinally of the car, and said washstand being foldable against one of the walls forming said corner to permit the bed to be moved between folded and operative positions.

6. In a railway car, a car floor, a lower room having standing space including a floor at substantially the level of the car floor, an upper room adjoining the lower room and separated therefrom by a partition having horizontally offset vertical portions connected by an upper horizontal portion supporting a seat for the upper room and a lower horizontal portion forming a floor for the upper room, and a movable bed for the lower room disposed in retracted position wholly in recesses beneath said upper and lower horizontal portions of the partition and movable to an extended position wholly clear of the recess beneath the lower horizontal portion and having one end portion in the standing space of the lower room and its other end portion in the recess beneath the upper horizontal portion of the partition, said bed when disposed in operative position having its longitudinal axis disposed longitudinally of the car and extending substantially full length of the lower room including the recess beneath the upper horizontal portion of the partition.

7. In a railway car having an upper level room provided with a seat, an adjoining lower level room separated from the upper level room by a partition and having a standing space wholly displaced longitudinally of the car from the upper level room, a movable bed disposed beneath the upper level room when in retracted position,

means mounting the bed for movement to an extended position in which the bed has its head portion in the standing space of the lower level room and its foot portion in a recess under the seat of the upper level room, and a bed in the upper level room movable between retracted and extended positions in both of which positions said bed is entirely displaced longitudinally of the car from the standing space of the lower level room, each of said beds when in operative position having its longitudinal axis disposed longitudinally of the car and extending substantially full length of the respective rooms.

8. In a railway car having an upper level room provided with a seat, an adjoining lower level room separated from the upper level room by a partition and having a standing space wholly displaced longitudinally of the car from the upper level room, a seat at the end of the lower level room opposite said partition, a movable bed disposed beneath the upper level room when in retracted position, means mounting the bed for movement to an extended position in which the bed has its foot portion in a recess under the seat of the upper level room and its head portion in the standing space of the lower level room and over the seat in the lower level room, and a bed in the upper level room movable between retracted and extended positions in both of which positions said bed is entirely displaced longitudinally of the car from the standing space of the lower level room, each of said beds when disposed in operative position having its longitudinal axis disposed longitudinally of the car and extending substantially full length of the respective rooms.

9. In a railway car having an upper room provided with a seat and a floor horizontally displaced therefrom longitudinally of the car, an adjoining lower room having a seat at one end, and a bed disposed beneath the upper room and slideable longitudinally from a recessed position under the seat and floor of the upper room to an extended position having one end portion overlying the seat in the lower room and having its other end portion under the seat of the upper room, said bed when disposed in operative position having its longitudinal axis disposed longitudinally of the car and extending substantially full length of the lower room including the portion of the lower room which is under the seat of the upper room.

10. In a railway car having an upper room provided with a seat having a recess beneath it and a floor horizontally displaced from the seat longitudinally of the car, an adjoining lower room having a seat at one end and facing an opening to said recess, and a bed for said lower room disposed in retracted position wholly beneath the upper room floor and in said recess and slideable longitudinally to an extended position having one end portion overlying the seat in the lower room and having its other end portion disposed wholly in said recess, said bed when disposed in operative position having its longitudinal axis disposed longitudinally of the car and extending substantially full length of the lower room including said recess.

11. In a railway car, a car floor, a lower room having standing space including a floor at substantially the level of the car floor, an upper room adjoining the lower room and separated therefrom by a partition having horizontally offset vertical portions connected by an upper horizontal portion supporting a seat for the upper room and a lower horizontal portion forming a floor for the upper room, a bed for the lower

room disposed in retracted position wholly in recesses beneath said upper and lower horizontal portions of the partition and slideable longitudinally to an extended position wholly clear of the recess beneath the lower horizontal portion and having one end portion in the standing space of the lower room and its other end portion in the recess beneath the upper horizontal portion of the partition, said bed when disposed in operative position having its longitudinal axis disposed longitudinally of the car and extending substantially full length of the lower room including the recess beneath the upper horizontal portion of the partition.

12. In a railway car, a car floor, a lower room having standing space including a floor at substantially the level of the car floor and having a seat at one end of said room, an upper room adjoining the lower room and separated therefrom by a partition having horizontally offset vertical portions connected by an upper horizontal portion supporting a seat for the upper room and a lower horizontal portion forming a floor for the upper room and providing respectively a high and a low recess open to the lower room at the end thereof opposite the lower room seat, and a bed for the lower room disposed in retracted position wholly in said recesses and slideable longitudinally to an extended position entirely out of the low recess and having one end portion in the high recess and the other end portion disposed in the standing space of the lower room and supported over the seat thereof, said bed when disposed in operative position having its longitudinal axis disposed longitudinally of the car and extending substantially full length of the lower room including the high recess thereof.

13. In a railway car having a central longitudinal aisle, a series of adjacent separate rooms upon each side of the aisle divided by fixed transverse walls and convertible respectively from sleeping rooms to sitting rooms, each alternate room of each series having a full length bed slideable horizontally in a direction longitudinally of the car from a position of use in said room to an inoperative position entirely beneath an adjacent room, and a pivoted bed in each of the remaining rooms of said series foldable endwise in a direction longitudinally of the car into a fixed transverse wall of its room directly over a portion of the bed of an adjacent alternate room, each of said beds when disposed in operative position having its longitudinal axis disposed longitudinally of the car and extending substantially full length of the respective rooms.

14. In a railway car having a plurality of independent rooms disposed between a side wall and an aisle wall and defined by partitions extending between said walls and convertible respectively from sleeping rooms to sitting rooms, certain of said partitions extending in a single plane from the floor to the ceiling of the car and alternating throughout the length of the car with partitions of relatively greater thickness with said rooms being disposed in pairs between like partitions, and a retractable bed in each room, the beds in alternate rooms being received in said partitions of relatively greater thickness when retracted and the beds in each of the remaining rooms being movable from an extended horizontal position in the respective rooms to a retracted position beneath the floor of an adjoining room, each of said beds when disposed in operative position having its longitudinal axis disposed longi-

tudinally of the car and extending substantially full length of the respective rooms.

15. In a railway car having a plurality of independent rooms disposed between a side wall and an aisle wall and defined by partitions extending between said walls and convertible respectively from sleeping rooms to sitting rooms, certain of said partitions extending in a single plane from the floor to the ceiling of the car and alternating throughout the length of the car with partitions of relatively greater thickness with said rooms being disposed in pairs between like partitions, and a retractable bed in each room, the bed in each alternate room being mounted for sliding movement from an extended horizontal position in the room to a retracted position beneath the floor of an adjoining room, each of said beds when disposed in operative position having its longitudinal axis disposed longitudinally of the car and extending full length of the respective rooms.

16. In a railway car having spaced longitudinally extending walls defining a central aisle, a plurality of independent rooms between the aisle walls and respectively opposing side walls of the car defined by partitions extending between the aisle and side walls, a bed pivotally mounted in each alternate partition and foldable endwise from a substantially vertical retracted position to a horizontal position occupying substantially the entire length of its room, and a full length bed slidably mounted beneath each alternate room and slideable longitudinally of the car to an extended position occupying substantially the entire length of its room, each of said beds when in operative position having its longitudinal axis disposed longitudinally of the car.

17. In a railway car having a plurality of independent rooms disposed between a side wall and an aisle wall and defined by partitions extending between said walls and convertible respectively from sleeping rooms to sitting rooms, a bed pivotally mounted in each alternate partition and foldable endwise from a substantially vertical closed position to a horizontal position occupying substantially the entire length of each alternate room, said bed when in operative position being of greater length than the normally usable sitting room space of its room, and a full length bed slidably mounted beneath each of the remaining rooms and slideable longitudinally to an extended position occupying substantially the entire length of its room, said last named bed having a fixed length greater than the normally usable sitting room space of its room, each of said beds when disposed in operative position having its longitudinal axis disposed longitudinally of the car.

18. In a railway car having a plurality of independent rooms disposed between a side wall and an aisle wall and defined by partitions extending between said walls and convertible respectively from sleeping rooms to sitting rooms, a full length bed, mounted in a recess beneath each alternate room and slideable longitudinally of the car to an extended position occupying substantially the entire length of the adjoining room including said recess, said bed having a fixed length greater than the normally usable sitting room space of said adjoining room and when disposed in operative position having its longitudinal axis disposed longitudinally of the car, and means for retaining said bed in recessed or extended position.

19. In a railway car having spaced longitudinally extending walls defining a central aisle, a

plurality of independent rooms between the aisle walls and respectively opposing side walls of the car defined by partitions extending between the aisle and side walls and disposed in contiguous relation at upper and lower levels, a bed pivotally mounted in each alternate partition and foldable endwise from a substantially vertical retracted position to a horizontal position occupying substantially the entire length of one of the rooms at the upper level, a horizontally disposed recess beneath each of the rooms at said upper level, and a full length bed slidably mounted in each recess and slidably longitudinally of the car to an extended position occupying substantially the entire length of a room at said lower level, each of said beds when disposed in operative position having its longitudinal axis disposed longitudinally of the car, said upper level bed having one end portion overlying one end portion of the lower level bed when the beds are extended.

20. A railway car having a plurality of independent rooms disposed between a side wall and an aisle wall and defined by partitions extending between said walls, certain of said partitions extending in a single plane from the floor to the ceiling of the car and alternating throughout the length of the car with partitions of relatively greater thickness, a pair only of said rooms being disposed between each adjacent pair of like partitions, and each of said partitions between the respective rooms of each pair being horizontally offset throughout its extent between said side and aisle walls to provide a fixed seat support of uniform width across substantially the full width of said rooms.

21. In a railway car, a pair of rooms disposed between a side wall and an aisle wall and defined by partitions extending between said walls, an intermediate partition separating said rooms and having a pair of stepped horizontal offsets, an aisle, a floor in one of the rooms on a level with the aisle floor, a doorway connecting said room with the aisle, the lower of the stepped horizontal offsets constituting a floor in the other room above the level of the aisle, a doorway connecting the second room with the aisle, stairs in the doorway from the aisle to said second room, a fixed seat in the second room disposed adjacent said intermediate partition at the higher of said stepped offsets, a fixed seat in the first room adjacent to one of said first-named partitions opposite said offsets and facing in the same direction as said first-named seat, a retractable bed for each room operable respectively to extended positions above and below said offsets and occupying substantially the entire length of the respective rooms, each of said beds when disposed in operative position having its longitudinal axis disposed longitudinally of the car, and storage space in each room accessible from the respective rooms.

22. In a railway car, a pair of rooms disposed between a side wall and an aisle wall and defined by partitions extending between said walls and convertible respectively from sleeping rooms to sitting rooms, an intermediate partition of relatively greater thickness separating said rooms and having a horizontally offset portion, a relatively fixed seat in one room disposed adjacent said intermediate partition at said offset portion, a relatively fixed seat in the other room adjacent to one of said first-named partitions opposite said offset portions and facing in the same direction as said first-named seat, a bed pivotally mounted in said intermediate partition and foldable endwise from a substantially vertical re-

tracted position to a horizontal extended position overlying said offset portion and occupying substantially the entire length of said one room, and a full length bed slidably longitudinally of itself and of the car to a position of use beneath said offset portion and occupying substantially the entire length of said other room, each of said beds when disposed in operative position having its longitudinal axis disposed longitudinally of the car.

23. In a railway car having an aisle, a side wall and an aisle wall, a room between the side and aisle walls having a floor above the level of the aisle floor, a partition defining one end of the room extending between said side and aisle walls, a second partition defining the other end of the room extending between said side and aisle walls and having an offset portion intermediate the floor and ceiling of said room, a doorway to the room in said aisle wall, a combination toilet member disposed in the room at one side of said doorway, a relatively fixed seat in the room at the other side of the doorway disposed adjacent to said second partition and mounted on the offset portion thereof and a retractable bed in the room pivotally mounted adjacent to said offset portion and foldable endwise into said last named partition, said bed when disposed in operative position having its longitudinal axis disposed longitudinally of the car and occupying substantially the entire length of the room between adjacent partitions and being of such width in relation to the distance between the side and aisle walls as to overlie the combination member and render such member inoperative in the extended position of the bed.

24. In a railway car having an aisle, a side wall and an aisle wall, a room between the side and aisle walls having a floor above the level of the aisle floor, a partition defining one end of the room extending between said side and aisle walls, a second partition defining the other end of the room extending between said side and aisle walls and having an offset portion intermediate the floor and ceiling of said room, a relatively fixed seat mounted on the offset portion, a retractable bed in the room having a section of less than full bed length pivotally mounted adjacent to said offset portion and foldable endwise into said last named partition, said section being adapted to be extended to a horizontal position defining substantially the length of the room between said partitions, and an extension member articulated to said section and automatically operable therewith to provide a full length bed extending into said second partition adjacent said offset portion and foldable into the partition when the bed is retracted, said bed when disposed in operative position having its longitudinal axis disposed longitudinally of the car.

25. In a railway car having an aisle, a side wall and an aisle wall, a room between the side and aisle walls, a partition defining one end of the room extending between said side and aisle walls, a second partition defining the other end of the room extending between said side and aisle walls and having an offset portion intermediate the floor and ceiling of said room, a doorway to the room in said aisle wall, a combination toilet member disposed in the room, a relatively fixed seat disposed transversely of the room adjacent said first-named partition, and a retractable bed for the room slidably mounted beneath said offset portion for movement horizontally into and out of the room, said bed when disposed in operative

position having its longitudinal axis disposed longitudinally of the car and being of such length in relation to the distance between said partitions as to have one end portion overlying said seat and its other end portion disposed beneath said offset portion when extended into the room and of such width in relation to the distance between said side and aisle walls as to overlie the combination member and render such member inoperative.

26. In a railway car having an aisle, a side wall and an aisle wall, a room between the side and aisle walls, a partition defining one end of the room extending between said side and aisle walls, a second partition defining the other end of the room extending between said side and aisle walls and having an offset portion intermediate the floor and ceiling of said room, a retractable bed for the room slidably mounted beneath said offset portion for movement horizontally into extended position in the room and into retracted position in a recess beneath said offset portion and having antifriction supporting means at spaced intervals along each side, a supporting track at one side of the bed adapted to be engaged by the supporting means on the bed and extending the full length of the bed and its movement, a supporting track at the other side of the bed adapted to be engaged by the supporting means on the bed and extending the full length of the bed, means adapted to lock the bed in retracted position, and means retaining the bed in extended position, said bed when disposed in operative position having its longitudinal axis disposed longitudinally of the car and extending substantially full length of the room, with an end portion in said recess.

27. In a railway car having a plurality of independent upper and lower rooms disposed between a side wall and an aisle wall and defined by partitions extending between said walls and convertible respectively from sleeping rooms to sitting rooms, a window in the side wall of each room, a doorway to each room in said aisle wall, a relatively fixed seat transversely disposed in each room adjacent the respective partitions all facing in the same direction and each arranged alongside one of said windows and at one side of one of said doorways, a toilet member in each room at the other side of said doorway, and a retractable bed in each room adapted to be extended to a horizontal position occupying substantially the entire length of its room, said bed when disposed in operative position having its longitudinal axis disposed longitudinally of the car and being of such length in relation to the distance between said partitions as to overlie the seat in the respective room and overlap the bed in the other room and of such width in relation to the distance between said side and aisle walls as to overlie said toilet member and render such member inoperative in the extended position of the bed.

28. In a railway car, two side walls and two end walls defining a passenger compartment, one of said end walls being provided with a recess and the opposite end wall comprising means dividing the compartment from an immediately adjoining compartment and separating a portion of the standing room space of the first compartment from a portion of the standing room space of the immediately adjoining compartment, a bed retractable in the direction of its length into said recess and extensible into the standing room space of said compartment, said bed when dis-

posed in operative position having its longitudinal axis disposed longitudinally of the car and extending substantially full length of the compartment between said end walls, and a combination toilet member in the corner formed by one of said end walls and one of the side walls and comprising a folding washstand and a hopper, said hopper being overlapped by the bed when the bed is extended to render the combination member inoperative.

29. In a railway car having a plurality of independent rooms disposed between a side wall and an aisle wall and defined by partitions extending between said walls and convertible respectively from sleeping rooms to sitting rooms, a bed pivotally mounted in each alternate partition and foldable endwise from a substantially vertical retracted position in said partition to a horizontal operative position extending substantially to the partition at the other end of the room, said bed when in said last named position having its longitudinal axis disposed longitudinally of the car and being of greater length than the normally usable sitting room space of the room and having an extension member articulated thereto and automatically operable therewith to provide a full length bed extending into said partition and foldable into the partition with said bed when the bed is retracted.

30. In a railway car having an aisle, a side wall and an aisle wall, a room between the side and aisle walls, a partition defining one end of the room extending between said side and aisle walls, a second partition of relatively greater thickness defining the other end of the room and extending between said side and aisle walls, a retractable bed in the room having a section of less than full bed length pivotally mounted to fold endwise into said last named partition and adapted to be extended to a horizontal operative position extending substantially to the partition at the other end of the room and defining substantially the length of the room between said partitions, and an extension member articulated to said section and automatically operable therewith to provide a full length bed extending into said second partition and foldable into the partition when the bed is retracted, said bed when disposed in operative position having its longitudinal axis disposed longitudinally of the car.

31. In a vehicle, a lower room and an upper room having its floor at a level higher than the floor of the lower room and wholly displaced longitudinally of the vehicle from the normally usable space of the lower room, a bed in the upper room retractable for daytime use of the room and wholly displaced longitudinally of the vehicle from the standing and seating area of the lower room, and a bed in the lower room under the bed of the upper room retractable for daytime use of the room and disposed adjacent to the floor of the upper room in retracted position, each of said beds when disposed in operative position having its longitudinal axis disposed longitudinally of the vehicle and extending substantially full length of the respective rooms.

32. In a railway car having a central longitudinal aisle, a series of adjacent separate rooms upon each side of the aisle divided by fixed transverse walls and convertible respectively from sleeping rooms to sitting rooms, certain of said rooms of each series including a portion underlying an adjacent room and each having a full length bed slidably horizontally in a direction longitudinally of the car from a position of use

in said room to an inoperative position entirely beneath said adjacent room, and each of said beds when disposed in operative position having its longitudinal axis disposed longitudinally of the car and extending substantially full length of its room.

33. In a railway car having a room defined by fixed transverse walls and convertible respectively from a sleeping room to a sitting room, said room having a bed including a pivoted section of less than full bed length foldable endwise in a direction longitudinally of the car into a recess of less than full bed length formed in one of said fixed transverse walls and a complementary extension member articulated thereto and adapted to provide therewith a full length bed and also foldable into said recess, said bed when disposed in operative position having its longitudinal axis disposed longitudinally of the car and extending substantially full length of the room from one transverse wall to the other.

34. In a railway car having a pair of independent rooms disposed between a side wall and an aisle wall and defined by partitions extending between said walls and convertible respectively from sleeping rooms to sitting rooms, a full length bed mounted beneath one room and slidable longitudinally of the car to an extended position occupying substantially the entire length of the adjoining room including a portion thereof underlying said one room, and said bed having a fixed length greater than the normally usable sitting room space of said adjoining room and when disposed in operative position having its longitudinal axis disposed longitudinally of the car.

35. In a railway car, a pair of rooms disposed between a side wall and an aisle wall and defined by partitions extending between said walls and convertible respectively from sleeping rooms to sitting rooms, an intermediate partition of relatively greater thickness separating said rooms, a relatively fixed seat in one room disposed adjacent said intermediate partition, a relatively fixed seat in the other room adjacent to one of said first-named partitions and facing in the same direction as said first-named seat, a bed pivotally mounted in said intermediate partition and foldable endwise from a substantially vertical retracted position to a horizontal extended position occupying substantially the entire length of said one room, and a full length bed slidable longitudinally of the car to a position of use occupying substantially the entire length of said other room, each of said beds when disposed in operative position having its longitudinal axis disposed longitudinally of the car and one of them having an end portion overlying an end portion of the other.

36. In a railway car having an aisle, a side wall and an aisle wall, a room between the side and aisle walls, a partition defining one end of the room extending between said side and aisle walls, a second partition defining the other end of the room extending between said side and aisle walls and having a recess of less than full bed length, a retractable bed in the room having a section of less than full bed length pivotally mounted adjacent to said last named partition, said section being foldable into said recess and being adapted to be extended to a horizontal position defining substantially the length of the room between said partitions, and an extension member articulated to said section and foldable therewith into said recess and automatically operable with said sec-

tion to provide a full length bed extending in horizontal operative position with its longitudinal axis disposed longitudinally of the car.

37. In a vehicle, a lower room, an upper room having its floor at a level higher than the floor of the lower room and wholly displaced longitudinally of the vehicle from the normally usable space of the lower room, a dividing partition between the rooms having a horizontal offset, a bed in the upper room adjacent said offset retractable for daytime use of the room and wholly displaced longitudinally of the vehicle from the standing and seating area of the lower room, and a bed in the lower room under the bed of the upper room retractable for daytime use of the room and disposed adjacent to the floor of the upper room, each of said beds when disposed in operative position having its longitudinal axis disposed longitudinally of the vehicle and extending substantially full length of the respective rooms.

38. In a vehicle, a lower room, an upper room having its floor at a level higher than the floor of the lower room and wholly displaced longitudinally of the vehicle from the normally usable space of the lower room, a dividing partition between the rooms having a horizontal offset, a bed in one of the rooms adjacent to said offset retractable for daytime use of the room and wholly displaced longitudinally of the vehicle from the standing and seating area of the other room, and a bed in the other room retractable for daytime use of the room disposed in vertically spaced parallel relation to the other bed when said beds are in operative position, each of said beds when in operative position having its longitudinal axis disposed longitudinally of the vehicle and extending substantially full length of the respective rooms.

39. In a vehicle, a lower room, an upper room having its floor at a level higher than the floor of the lower room and wholly displaced longitudinally of the vehicle from the normally usable space of the lower room, a dividing partition between the rooms, a bed in one of the rooms adjacent said partition retractable for daytime use of the room and wholly displaced longitudinally of the vehicle from the standing and seating area of the other room, and a bed in the other room retractable for daytime use of the room disposed in vertically spaced parallel relation to the other bed when said beds are in operative position, each of said beds when in operative position having its longitudinal axis disposed longitudinally of the vehicle and extending substantially full length of the respective rooms.

40. In a railway car, a pair of rooms disposed between a side wall and an aisle wall and defined by partitions extending between said walls and convertible respectively from sleeping rooms to sitting rooms, an intermediate partition separating said rooms, a bed pivotally mounted in said partition and foldable endwise from a substantially vertical retracted position in the partition to a horizontal extended position occupying substantially the entire length of one room, and a full length bed slidable longitudinally of the car to a position of use occupying substantially the entire length of the other room, each of said beds when disposed in operative position having its longitudinal axis disposed longitudinally of the car.
